UNITED STATES PATENT OFFICE.

THOMAS GROSERT, OF NEW YORK, N. Y.

HAIR-WAVER.

1,085,088.

Specification of Letters Patent. Patented Jan. 20, 1914.

Application filed January 18, 1912. Serial No. 742,944.

To all whom it may concern:

Be it known that I, Thomas Grosert, a citizen of the United States, and a resident of the city of New York, borough of Manhattan, in the county and State of New York, have invented a new and Improved Hair-Waver, of which the following is a full, clear, and exact description.

My invention relates to a waver used in forming permanent waves or undulations to the hair on a person's head.

The primary object of my invention is to provide a means by which a strand of hair can be waved into regular and uniform undulations.

Other and incidental objects will be suggested by the following description, it being understood that the disclosure is but one means of performing the object above outlined.

With the cylindrical form of curlers now in general use in one of the preliminary steps of waving hair, it has been found that the waving was less pronounced close to the head than it was toward the end of the hair due to the fact that the strands of hair were thicker, that is contained more hairs, close to the head. In order to obviate this irregular waving it has been known to space the coils relatively close together close to the head and spread them farther and farther apart toward the end of the strand. Obviously this method is defective in that the pitch of the coil is hardly ever uniform on two different curlers.

I overcome the above indicated difficulties by wrapping the strands of hair about a curler so constructed that the coils will have progressively greater diameters from the end of the curler adjacent the head toward the other end. This wrapping of the hair when treated by a known method will result in a regularity of waves.

Reference is to be had to the accompanying drawings, forming a part of this specification, in which similar characters of reference indicate corresponding parts in all the figures, and in which—

Figure 1 is a perspective view of a head of hair showing a strand wrapped about my improved curler. Fig. 2 is a side view of a preferred form of curler and Fig. 3 is a

side view of a slightly modified form of curler.

My curler resembles the conventional perforated tube now used for this purpose except that the end adapted to be placed adjacent the head is of progressively reduced diameter toward this end. As a part of the process of waving the hair, a straight strand is wrapped or coiled in one layer evenly and closely about the curler disclosed. This curler A is shown to be a tapered tube, or as shown in Fig. 2, to have one end tapered from a cylinder, B to form a frusto conical portion. The small end of which tube is closed preferably by means of a button or knob C adapted to bear on the head or rather on the protecting head covering used in the method of waving the hair.

After the hair is wrapped on the curler as herein described it is subjected to a chemical steaming as more fully described in my application Serial No. 712,977, allowed November 26, 1912.

Having thus described my invention, I claim as new and desire to secure by Letters Patent:

1. A hair waver for use in forming the hair on a person's head into uniform waves, said waver comprising a straight rod including a cylindrical portion and a frustoconical portion converging from an end of said cylindrical portion and a head-engaging knob on the small outer end of said frusto-conical portion.

2. A hair waver for use in waving hair on a person's head, comprising a straight rod adapted to have a strand of hair uniformly coiled about the same, said rod having a knob closing one end thereof and adapted to bear on the head of the person, the portion of the rod adjacent the knob converging toward the knob whereby the progressively thicker coils of hair may be arranged in succession on progressively smaller portions of the waver.

In witness whereof I have hereunto set my hand in the presence of two witnesses.

THOMAS GROSERT.
